DESIGN FOR A COMBINED EJECTOR PUMP
AND STRAINER BASE PLATE

Walter B. Harris, Southold, N. Y.

Application August 13, 1946, Serial No. 132,476

Term of patent 7 years

(Cl. D65—1)

To all whom it may concern:

Be it known that I, Walter B. Harris, a subject of the King of Great Britain, residing in Southold, Long Island, county of Suffolk, and State of New York, have invented a new, original, and ornamental Design for a Combined Ejector Pump and Strainer Base Plate, of which the following is a specification, reference being had to the accompanying drawing, forming part thereof.

Figure 1 is a front elevational view of a combined ejector pump and strainer base plate, embodying my new design; and

Figure 2 is a top plan view thereof.

I claim:

The ornamental design for a combined ejector pump and strainer base plate, as shown.

WALTER B. HARRIS.
